UNITED STATES PATENT OFFICE

2,468,650

PAPER PAD FRAME

Garfield L. Beckstrom, Chicago, Ill., assignor to
Autopoint Company, Chicago, Ill., a corpora-
tion of Illinois

Application December 7, 1944, Serial No. 567,057

14 Claims. (Cl. 281—15)

1

This invention relates to a frame for holding a paper pad or the like, and may be used on a desk, table or other suitable place for holding a pad of paper sheets for memorandum purposes, a pad of calendar sheets, a pad of sheets with reference data, or a paper pad for any other purposes.

Among the objects of my invention is to provide a desk pad frame possessing the above mentioned advantages, and being of pleasing and attractive appearance and easy and economical to manufacture.

Another object is to provide novel means for securing the paper pad in the frame and enabling quick and easy application of the pad to, and removal of the same from, the frame.

A further object is to provide novel means for firmly securing the upper clamping plate to the frame, which frame is of plastic or other ornamental material.

Other objects, advantages and capabilities, inherently possessed by my invention, will later more fully appear.

My invention further resides in the combination, construction and arrangement of parts illustrated in the accompanying drawings, and while I have shown therein a preferred embodiment, I wish it understood that the same is susceptible of modification and change without departing from the spirit of my invention.

In the drawings:

Fig. 1 is a side edge elevation of a paper pad frame and paper pad, embodying my invention.

Fig. 2 is a top plan view of Fig. 1 with portions broken away for the sake of clearness.

Fig. 3 is a longitudinal vertical section on the line 3—3 of Fig. 2.

Fig. 4 is a front elevation looking toward the right hand side of Fig. 2.

Fig. 5 is a perspective view, on a reduced scale, of a paper pad and associated parts detached from the frame.

Fig. 6 is an enlarged fragmentary vertical longitudinal section taken on the line 6—6 of Fig. 2.

Referring more in detail to the drawings, my invention comprises a head or main body portion 1 within which is secured an upper plate 2 of metal or other durable material having a pair (or other suitable number) of countersunk openings 3 in which are mounted the tapered heads 4 of threaded rods or pins 5, on the threads 6 of each of which pins is threadably mounted a wing nut 7, these pins passing through holes 8 in the bottom plate 9 and the wing nuts bearing against the lower face of the bottom plate to

2

clamp a pad 10 of sheets of paper or the like between the upper plate 2 and the bottom plate 9 when the wing nuts are tightened against the bottom plate. While for illustrative purposes only I have shown and described the elements 5 as threaded pins having wing nuts I wish it understood that other forms of tightening elements may be used as are adapted to the purpose intended.

10 The head or body portion 1 is preferably formed of either thermoplastic or thermosetting plastic material, but if desired may be formed of any other ornamental material suitable to the purpose intended. It is constructed with a depending portion or portions 11 of a suitable length the bottom end or ends of which rest upon the desk, table, or other supporting surface a. For ornamental purposes, and to prevent the undesirable entry underneath thereof of objects, the head 11 is formed with a wall 12 extending between the depending portions 11. If it should be desired to omit the depending portions 11 as individual parts, I wish it understood that the wall 12 may be extended downwardly in any desired shape 15 to rest upon the desk, table or the like to provide the desired support and height for the device.

Extending forwardly from the depending portions 11 and the wall 12, is an upper cover portion 13 having side cheeks 14, one on each side, provided with forwardly extending side walls 15, one on each side, spaced apart laterally a distance to readily receive therebetween one end of the pack 10 of paper sheets referred to generally 20 herein as a paper pad. Each of the side cheeks 14 on the inner side at the juncture of the side cheeks and the cover portion 13 is formed with a slot or groove 16—17 as shown in Figs. 2 and 4, to receive the side edges 18—19 of the upper plate 2 to hold the latter and the paper pad secured thereto in proper position laterally and vertically with relation to the head or body portion 1. Plate 2 is formed along the upper rear edge with an elongated burr or slight upstanding flange 20, 25 which is shown somewhat exaggerated in the drawings for the sake of clearness. When the head portion 1 is formed of plastic material the plate 2, with the rods or pins 5 in place therein, is forced into place by sliding the edges 18—19 rearwardly in the grooves 16—17 and forcing the burr or flange 20 along the under surface of the cover 13 while the plastic material is still green or uncured (as it would be when freshly removed from the mold) and before the plastic head has 30 shrunk to its final position. When the plate 2

reaches its limit of movement the burr or slight flange 20 will jump into the groove or notch 21 formed in the plastic material of the head 1, as in Fig. 6. As soon as the plastic material has completed its shrinking and reached its final set the burr or flange 20 will be firmly seated in the groove 21 and the plate 2 thus securely anchored in place with the rods, pins, or other pad securing means extending downwardly to receive the paper sheets of the pad, which sheets have registering holes so that these pins or the like may be passed through the said holes and the pad secured to the frame by tightening the wing nuts 1 against the bottom plate 9 which has corresponding holes and is positioned at the bottom of the pad.

The bottom plate 9 is formed of any desirable material such as "Masonite," metal, wood, impregnated wood, composition board, or other suitable material. The respective sheets of the pad, when desired, may be removed by tearing them off along the adjacent forward lower edge of the plate 2. If preferred the sheets may each have an open slot extending to their rear edge from each of the holes receiving the pins 5 and the wing nuts adjusted with sufficient slack in the pins to normally hold the sheets of paper in position in the frame and yet permit them to be individually removed by a forward pull, the wing nuts being adjusted from time to time as desired to give the desired gripping action to the sheets. When the sheets are torn off as suggested above, it will not be necessary to further adjust the wing nuts for that pad as the stub ends will remain in place to maintain the gripping action on the pad. When a new pad is to be inserted the wing nuts, or other fastening means, will be removed, a new pad inserted, and the fastening means again tightened.

As seen in Figs. 1 and 3 the head 1 is of sufficient height that when the pad is assembled therein the rear or adjacent portion of the pad and wing nuts will be above and clear the surface *a* of the desk or the like, while the lower forward edge of the pad will rest thereon, which will position the upper surface of the pad at such inclination as to make it readily available and convenient for reading or writing purposes.

From the above it is seen that when once assembled the upper plate 2 remains in the head 1 and the pins 5, or other fastening means, remain in the plate 2. This enables a quick removal of a used pad from the frame, and the quick and easy insertion of a new pad therein.

Having thus described my invention, I claim:

1. A paper pad frame comprising a head for resting upon a desk, table and the like, an upper clamping plate disposed within and secured to the head, supporting means on the upper clamping plate concealed within the head, a bottom plate for receiving thereon a pad of paper sheets positioned on said supporting means between said plates, and means for clamping the pad between the plates, said supporting means comprising a pin depending from the upper clamping plate.

2. A desk pad frame comprising a hollow head, an upper clamping plate fixed to the underside of the upper wall of the head, a supporting pin depending from the upper clamping plate from below the upper wall for receiving a pad of paper sheets having registering holes through which the supporting pin extends, clamping means on the pin for clamping one end of the pad in the hollow head, and a lower plate carrying the pad,

the clamping means bearing against the lower plate.

3. A frame for supporting a pad of paper sheets, and comprising a hollow head having in its upper interior a pair of laterally inwardly opening grooves, a plate whose side edges are mounted in said grooves, means on said plate for supporting a pad, said hollow head being formed in its upper interior with a laterally extending groove, and a projection on the plate seated in the last mentioned groove.

4. A frame for holding a pad of paper sheets and the like, comprising a hollow head having a cover and side walls, said head being formed with longitudinally extending inwardly opening grooves in the junctures between the cover and the side walls, a supporting plate having its side edges mounted in said grooves, said cover being formed on its inner face with a laterally extending indentation, a projection on the rear edge of the plate seated in the indentation, said plate having a countersunk opening therethrough, a pin having a tapered head seated in said countersunk opening to have its adjacent outer end within the confines of the thickness of the plate, said pin being adapted to receive a pad of paper sheets, and pad-clamping means on the pin.

5. A frame for holding a pad of paper sheets and the like, comprising a hollow head having a cover and side walls, said head being formed with longitudinally extending inwardly opening grooves in the junctures between the cover and the side walls, a supporting plate having its side edges mounted in said grooves, said cover being formed on its inner face with a laterally extending indentation, a projection on the rear edge of the plate seated in the indentation, said plate having a countersunk opening therethrough, a pin having a tapered head seated in said countersunk opening to have its adjacent outer end within the confines of the thickness of the plate, said pin being adapted to receive a pad of paper sheets, and pad-clamping means on the pin.

30 6. A frame for supporting a pad of paper sheets, comprising a hollow head formed of a synthetic resinous plastic material and having secured in its upper interior a supporting plate, a depending pin projecting from the plate and disposed wholly beneath the head for receiving a pad of paper sheets, and means on said pin securing a pad of paper sheets to the supporting plate.

7. A paper pad frame comprising a head for resting upon a desk, table and the like, an upper clamping plate disposed within and secured to the head, supporting means including a depending member on the upper clamping plate concealed within the head, a bottom plate for supporting thereon a pad of paper sheets positioned on the depending member, and means for retaining the pad upon the depending member and between the plates.

8. A desk pad frame comprising a hollow head, an upper clamping plate fixed to the underside of the upper wall of the head, a supporting pin depending from the upper clamping plate from a position below the upper wall for receiving a pad of paper sheets having registering holes through which the supporting pin extends, and clamping means on the pin for clamping one end of the pad in the hollow head.

9. A desk pad and frame, comprising a hol-

low head having on its interior a pair of laterally spaced longitudinally extending grooves, an upper clamping plate having its lateral edges positioned in said grooves, said clamping plate having depending supporting means for receiving a pad of paper sheets, and means for clamping one end of the pad upon the supporting means and against the clamping plate.

10. A desk pad and frame, comprising a hollow head having on its interior a pair of laterally spaced longitudinally extending grooves, an upper clamping plate having its lateral edges positioned in said grooves, said clamping plate having depending supporting means for receiving a pad of paper sheets, a lower plate carrying the pad, and fastening means on the supporting means for clamping one end of the pad against the clamping plate and positioning and retaining the pad between the lower plate and the clamping plate.

11. A desk pad frame for supporting a pad of paper, comprising a hollow head for resting on a desk, table and the like, said head having a cover member formed with a longitudinal inwardly opening groove on the interior of each of its side portions, a clamping plate disposed beneath the cover member with its side edges mounted in the grooves and having depending supporting members for receiving an end of the pad beneath the clamping plate, and fastening means on the supporting members for retaining the pad in the frame and against the clamping plate.

12. A desk pad frame for supporting a pad of paper, comprising a hollow head for resting on a desk, table and the like, said head having a cover member formed with a longitudinal inwardly opening groove on the interior of each of its side portions, a clamping plate disposed beneath the head with its side edges mounted in 40

the grooves and having depending members for receiving an end of the pad, and means on the depending members for securely but removably clamping the end of the pad on these members and against the clamping plate.

- 5 13. A frame for holding a pad of paper sheets and the like, comprising a hollow head having side walls spaced apart a distance to receive one end of a pad, a supporting plate positioned with 10 in the hollow head and securely mounted on the side walls, and depending projections on the plate and wholly disposed within the head for receiving and holding the pad.
14. A frame for holding a pad of paper sheets and the like, comprising a hollow head having side walls spaced apart a distance to receive one end of a pad, a supporting plate positioned within the hollow head and engaging the side walls, means for anchoring the supporting plate in the side walls, and depending supporting members 20 on the plate and wholly disposed within the head for receiving and securely retaining the pad in the frame.

Certificate of Correction

Patent No. 2,468,650.

April 26, 1949.

GARFIELD L. BECKSTROM

It is hereby certified that error appears in the printed specification of the above numbered patent requiring correction as follows:

Column 4, line 5, claim 3, after the word "laterally" insert *spaced*;
and that the said Letters Patent should be read with this correction therein that the same may conform to the record of the case in the Patent Office.

Signed and sealed this 11th day of October, A. D. 1949.
